UNITED STATES PATENT OFFICE.

HENRY C. KARR, OF WASHINGTON, DISTRICT OF COLUMBIA.

DESIGN FOR A SPOON, &c.

SPECIFICATION forming part of Design No. 20,781, dated May 26, 1891.

Application filed March 28, 1891. Serial No. 386,853. Term of patent 3½ years.

To all whom it may concern:

Be it known that I, HENRY C. KARR, a citizen of the United States, residing at Washington, in the District of Columbia, have invented a certain new and original Design for Spoons, Forks, and Similar Articles; and I do hereby declare the following to be a full, clear, and exact description of the same.

In the accompanying drawing I have shown 10 a tea-spoon embodying my design.

The leading feature of my design consists in a representation of "Uncle Sam" as the handle of the article. This familiar figure is represented in the drawing as standing in an 15 erect position with his right hand in his trousers-pocket and his left hand twirling his beard. A smile appears on his face and his hat is pushed slightly back from his forehead.

In the drawing, A designates the bowl of the spoon, and B the handle thereof, which, 20 as shown, is formed by the representation of "Uncle Sam." The figure is represented as standing on a base or support D.

Having thus described my design, what I claim, and desire to secure by Letters Patent, 25 is—

The design for spoons, forks, and similar articles herein described and shown.

In testimony whereof I have hereunto affixed my signature in the presence of two witnesses. 30

HENRY C. KARR.
